Cyrus N. Anderson
ATTORNEY

UNITED STATES PATENT OFFICE.

CORNELIUS DANIELS, OF PHILADELPHIA, PENNSYLVANIA, ASSIGNOR OF ONE-HALF
TO JULIUS R. BUX, OF PHILADELPHIA, PENNSYLVANIA.

RACK FOR ACTUATING THE SHUTTLES OF NARROW-WARE LOOMS.

Application filed February 26, 1927. Serial No. 171,133.

My invention relates to improvements in racks which are employed to effect or cause reciprocatory movements of the shuttles embodied in looms for weaving narrow-ware fabrics. In narrow-ware looms the shuttles and the immediately cooperating means associated therewith for the actuation thereof are located at intervals and the said means is adapted to be operated by means of a rack 10 common to all of the said shuttles and the said means immediately associated therewith.

Heretofore these racks have consisted of fibre or wood and the construction usually has embodied a wooden bar of suitable 15 dimensions having in one side thereof a slot within which a wooden rack has been mounted and secured usually by cement. These racks frequently are of considerable 20 length, say 20 feet more or less, and their construction has involved relatively great expense. A further expense incident to said wooden racks has been due to the fact that they become worn in relatively short periods 25 of time whereby they become unfit for further use. In other words, such wooden racks have been lacking in durability.

The general object of the present invention is to provide a rack of novel construction of 30 a character such that its use may be continued indefinitely because of its great durability.

It also is an object of the invention to provide a rack of novel construction consisting 35 preferably of a wooden bar having a slot in one side thereof within which is located a rack of sheet metal crimped to form teeth therein of the proper dimensions and in proper spaced relation with respect to each other.

In order that the invention may be readily 40 understood and its practical advantages fully appreciated reference may be had to the accompanying drawing in which I have illustrated one form of embodiment thereon. 45 However, it will be understood that changes in details of construction may be made within the scope of the claims without departing from the said invention.

In the drawing

Fig. 1 is a view in elevation of three shuttles 50 with the blocks provided with raceways through which the shuttles are adapted to be reciprocated and also showing gears in elevation which are adapted to be actuated by the

reciprocation of the rack bar, the latter being shown in longitudinal section; and

Fig. 2 is a view in perspective of a portion of a rack bar with a part thereof broken away and sectioned in order that the crimped rack strip may be more clearly exposed to view.

In the drawing I have shown three blocks 1, each of which is provided with raceways 2 and 3 which extend crosswise of each other as shown. Each of the shuttles 4 operates in one of the raceways of two adjoining blocks 65 as is clearly indicated in Fig. 1 of the drawing. Each of the shuttles is provided with teeth 7 which are adapted to be engaged by the teeth of the spur gears 8 mounted in co-operative relation with respect thereto, all in 70 known manner.

For the purpose of causing oscillatory rotative movements of the gears 8 to effect reciprocatory movements of the shuttles 4 in the raceways of the blocks 1, a rack is employed which rack embodies the present invention. The said rack comprises a bar 10, preferably of wood, within the upper side of which is provided a slot 11. Within the said slot rack teeth 12 are provided. These teeth 80 are formed by crimping or corrugating a relatively thin metal strip 13. Such crimping may be effected in any desired known manner. The size of the teeth and the spacing thereof may be varied in order to adapt the same to the teeth of the gears 8 with which they must mesh in the operation of the same. The strip 13 crimped and corrugated as shown is located within the slot 11 and may be fastened or secured therein in any desired known 85 manner. Cement or any other means suitable for the purpose may be employed for fastening the same permanently within the 90 said slot.

A rack consisting of a crimped or corrugated sheet metal strip may be constructed at a minimum of cost or expense, yet its durability is very much greater than a rack of wood which might be located within the slot 11 and employed for operating the gears 8. As has been suggested already the rack for operating the gears 8 may be of considerable length, say 20 feet more or less. The advantage therefore of using a rack made of a narrow strip of relatively thin sheet metal 105 is apparent because the rack may consist of a single integral strip. In the case of wood it is not practical to form the teeth in a

single strip of wood provided the rack is of the length above indicated, but instead of employing a single long strip the teeth are formed in a greater or less number of relatively short strips, which then are placed in end to end relation in the slot 11 and secured in place therein. It will be apparent therefore that it would cost very much less to produce a rack bar comprising a rack made of a narrow strip of relatively thin sheet metal than if the said rack consisted of wood having teeth formed therein.

In a narrow-ware loom of the character of that referred to herein in which a rack embodying my invention is adapted to be employed for effecting reciprocation of the shuttles 4 which carry the weft or filling to be laid in the shed formed in the warp threads, means is provided for effecting reciprocal movements of the rack, but such means is not shown because it constitutes no part of my invention and because any known means for that purpose may be employed. The rack is in engagement with the gears 8 and reciprocation thereof causes oscillatory movement of the said gears and the latter being in engagement with the gear teeth upon the bottom sides of the shuttles 4 effects reciprocal movements thereof in the raceways 3 in the blocks 1 through the paths as indicated in Fig. 1 of the drawing. The bar 10 with the rack 13 supported thereon may be supported in any suitable known manner. I

have indicated a fragmentary portion only at 15 of means which may be employed to 35 slidably support the said bar.

By my invention I am enabled to provide at relatively low cost a rack for use in the operation of the shuttles of narrow-ware looms which racks are characterized by their great durability, and by my invention I have also produced a structure in which there is a minimum amount of friction between the rack and the gears actuated thereby.

Having thus described my invention, what I claim and desire to secure by Letters Patent is:

1. A rack for actuating the shuttles of narrow-ware looms consisting of a wooden bar and a rack mounted thereon consisting of a narrow strip of sheet metal corrugated to form rack teeth which are adapted to engage means for actuating the said shuttles.

2. A rack for actuating the shuttles of narrow-ware looms which consists of a bar of wood having a slot in one side thereof, which slot extends longitudinally of the said bar, a narrow metal strip crimped to form projections at intervals therein constituting gear teeth located within the said slot, and means for securing said crimped strip within said slot.

In testimony that I claim the foregoing as my invention I have hereunto signed my name this 25th day of February A. D. 1927.

CORNELIUS DANIELS.
